202,597

WINTER SOLARIUM APARTMENT

Mike Tecton, 5101 45th St. NW., Washington, D.C.

Filed Nov. 25, 1964, Ser. No. 82,785

Term of patent 14 years

(Cl. D83—1)

FIG. 1

FIG. 2

FIG. 3

FIG. 4

FIGURE 1 is a front perspective view of a winter solarium apartment embodying my new design;
FIGURE 2 is a top plan view thereof;
FIGURE 3 is a rear elevational view thereof;
FIGURE 4 is a side elevational view thereof.
I claim:

The ornamental design for a winter solarium apartment, substantially as shown.
